Primary Examiner — Paula Allen Greene*(74) Attorney, Agent, or Firm* — Ying-Ting Chen(57) **CLAIM**

The ornamental design for a earphone as shown and described.

DESCRIPTION

FIG. 1 is a front view of an earphone showing my new design according to a first embodiment;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a front perspective view thereof;

FIG. 8 is a rear perspective view thereof;

FIG. 9 is a front view of the earphone showing my new design according to a second embodiment;

FIG. 10 is a rear view thereof;

FIG. 11 is a left view thereof;

FIG. 12 is a right view thereof;

FIG. 13 is a top view thereof;

FIG. 14 is a bottom view thereof;

FIG. 15 is a front perspective view thereof; and,

FIG. 16 is a rear perspective view thereof.

1 Claim, 16 Drawing Sheets(56)
